UNITED STATES PATENT OFFICE.

AILENE BABB AND EDWARD B. HARRIS, OF HILLSBORO, OREGON.

FRUIT-PACKING MACHINE.

1,412,991.

Specification of Letters Patent. Patented Apr. 18, 1922.

Application filed February 14, 1921. Serial No. 444,757.

To all whom it may concern:

Be it known that we, AILENE BABB and EDWARD B. HARRIS, both citizens of the United States, residing at Hillsboro, in the county of Washington and State of Oregon, have invented a new and useful Fruit-Packing Machine, of which the following is a specification.

Our invention relates to improvements in fruit packing machines in which fruit is received from a grader, automatically wrapped in paper deposited in layers in a box, the latter shifted out of the way and an empty box put into its place.

The objects of our invention are to construct a machine which will replace manual labor in the wrapping and packing of apples, oranges, lemons, pears, and similar fruits.

Other objects and advantages will appear from the description given hereinafter.

We attain these objects with the mechanism illustrated in the accompanying drawings, in which—

Fig. I is a perspective view of the entire machine as seen from the rear end, i. e. that end from which the wrapping paper and the empty boxes are supplied.

Fig. II is a plan view of the table to show the relative position of the paper carrying chains, the wrapping paper, the paper knife, and the grader chute.

Fig. III is a front elevation of the machine.

Fig. IV is a right hand elevation to an observer standing at the front of the machine and looking toward the rear.

Fig. V is a left hand elevation.

Fig. VI is a detail of the mechanism which packs the fruit into the box, the section being taken along the line A—A, in Fig. II.

Fig. VII is a perspective view of the slide which shifts the wrapped fruit from one piston to the other.

Fig. VIII is a perspective view of the chain links which convey the wrapping paper across the table.

Fig. IX is the section through Fig. III along the line B—B mainly to show the two box shifting frames in plan view.

Fig. X is a detail of the pawl arrangement which gives the intermittent horizontal motion to the frames shown in Fig. IX.

Fig. XI is a section through the frames along the line C—C in Fig. IX.

Fig. XII is a section through the frames along the line D—D in Fig. IX.

Similar numerals refer to similar parts throughout the several views.

A table 1 rests on suitable supports 2, to which latter also a large part of the mechanism underneath the table is attached. A roll of wrapping paper 3, located at the rear end of the table, unwinds over an auxiliary roller 4. The edges of the strip of paper are caught by the clips 5 of the paper carrying chains 6 and led over the surface of the table 1. A knife 7 descends at regular intervals to sever the forward end of the paper just at the moment when the paper has arrived over the opening 8, (Fig. VI) in the table. Simultaneously the fruit rolls down from the grader chute 9, and a piston 10 descends, pressing the fruit through the opening into a tunnel 11 under the table, and thereby automatically closing the paper around the fruit at the bottom and sides. A bell-shaped piston 10 is employed, partly to cause less injury to the fruit, and partly for reasons which will be explained later.

The fruit having arrived in the tunnel is taken hold of by a sliding frame 11' and pulled over to one side where another piston 12 descends and presses the fruit through a tube 13 into a box 14. Moving the fruit in the tunnel away from the piston 10 leaves the latter free to ascend and clear the way for a new strip of paper, moreover this lateral motion causes one side of the created paper tube to fold over the top of the fruit and thus to cover the latter completely. The lower end of the tube 13 should terminate high enough above the deposited fruit to permit the box to slide horizontally without interference between the deposited fruit and the tube.

Our next consideration is directed to the mechanism which imparts to the box 14 a lateral motion in horizontal direction and permits the fruit to be placed side by side. For this purpose the box 14 is surrounded by a fairly close fitting frame 15, with a pusher bar 16 projecting toward the left-hand side of the machine. This bar is engaged at one end by a bell-crank 17, the other end of which is actuated by a hook 18 attached to

a slideable ratchet bar 19. A forward and backward motion of the ratchet bar is effected by the two pawls 20, shown in detail in Fig. X. There it is shown that the pawls 5 are pivoted to the lever 21, and connected by a link 22, so that one pawl will engage the ratchet bar when the other pawl is lifted clear off the teeth of the ratchet bar. The lever 21 being fulcrumed at 21' to the 10 support 2 (see also Fig. V), an oscillatory motion is produced, first in one direction by a timing rod 23 which is actuated by a suitable timing gear 24 on the main shaft 25, and then in the opposite direction by a tension 15 spring 26.

As soon as one pawl has shifted the ratchet bar to the end of its travel a hump 27 will lift this pawl clear off the teeth and automatically force the companion pawl to engage 20 the teeth at the other side of the ratchet bar 19. Since these teeth point in the opposite direction the ratchet bar must travel backward to its original position and thereby carry through the intervention of bell 25 crank, arm, and frame, the box 14 within the frame 15 back to the left-hand side.

However, before the box starts its return journey a pawl and ratchet arrangement similar to the one described enters into action; 30 the same is placed on the right-hand side as shown in Fig. IV. Again the pawl lever 28 with pawls 28', is oscillatingly secured to the supporting frame 2, while the ratchet bar 29 in this case is affixed directly 35 to the large frame 30 which encloses the small frame 15 and therefore will shift the box a corresponding distance forward or backward as the case may be. A timing rod 31 at the pawl lever 28, operated by a timing gear 32 40 on the main shaft, produces the motion in one direction, and the tension spring 33 takes care of the motion in opposite direction. The timing gear 32 should be properly timed to make one motion after the timing gear on 45 the left-hand side has shifted the box laterally into the last position.

To lower the box automatically, in order to place one layer of fruits on top of the other, the platform 34 on which the box rests 50 is provided on both sides with upwardly extending ratchet bars 35, which are suspended from the pawls 36, in such a manner that, when one pawl is released, the opposite pawl on the same ratchet bar is ready to engage 55 a tooth. The pawls 36, must necessarily be affixed to the supporting frame 2, and be set in operation by the pins 36' when the box has arrived at the end of its travel in forward or backward direction.

60 After the platform 34 has reached its lowest position, that is, after the last layer of fruit has been deposited, the box has dropped below the embrace of the frames 15 and 30, and a carrier chain 37 is set in motion. The 65 prongs 38 of the carrier chain shift the full

box out of the way onto a nailing platform (not shown) and simultaneously place an empty box in its place. The empty boxes are placed in position on a plank 39, by a timing device which however at present may 70 be omitted from consideration.

The next step is to elevate the platform 34 with its box 14 to begin again with the deposition of the bottom layer of fruit. For this purpose toggles 40, (Figs. I, IV, and V) 75 are provided between platform and floor, said toggles being joined by a timing bar 41, which again is operated by a suitable timing gear 41', so that at the proper moment the toggles will straighten out and lift platform and box 80 to the requisite height whereupon the previously described sequence of operation may begin anew.

The general principle of our machine has thus been stated. 85

It remains to revert to some details which have been shown in the drawing but not touched upon heretofore. A small bench 42 on the table 1 serves as a support for the lower end of the grader chute 9 and must 90 naturally be provided with a hole 43 through which the fruit may drop down to the paper underneath. A clutch lever 44 is mounted oscillatorily over this bench to swing forward when no fruit is coming down the 95 chute. A slot 45 at one side of the bell-shaped piston 10 leaves sufficient freedom for the lever to swing forward until it comes to a stop at the lower opposite edge of the piston. The clutch lever 44 may be supported on the table 1 in any suitable manner, but should have an arm 45' hanging down over the edge of the table (see Fig. IV). From the lower end of the arm 45' reaches 100 a link 46 to the lever 47, and the latter actuates a suitable clutch 48 on the main shaft 25. A forward oscillation of the lever 44 disengages the clutch 48 and sets the entire machine at rest until the next fruit runs down the grader chute 9, presses the lever 44 110 aside and starts the machine going again.

To give the paper knife 7 a snappy up and down motion, a shaft 49 at the left-hand side of the machine (Figs. I and V) is driven by suitable gears 50 from the main shaft 25, 115 and on the shaft is mounted a spiral spring 51 which is put under tension by the rotation of the shaft. This tension exerts itself on the knocker arm 52 whenever the same is released. This arm in flying around the 120 shaft knocks against a hook 53 hanging down from the handle of the paper knife 7 and forces the knife down. Disengaging itself from the hook, the arm flies further around the shaft back into a vertical position, while the paper knife is just as quickly pressed upward by a compression spring 54. The shaft 49 also contains the crank 55 which operates the fork 56 on the sliding frame 11', and the crank 57 which oper- 125 130

ates the piston 12. At the right hand side of the machine the shaft 58, which contains the crank 59 for the bell-shaped piston 10, is also driven by the main shaft, as in fact every other operation in this machine is governed from the main shaft through the interposition of suitable timing gears and counter shafts.

Figs. IX and XII show the pusher bar 16 in the frame 15 working in a slot 60. The necessity for this arrangement will be clear when it is understood that the small frame 15, besides having its own motion in lateral direction, must also be able to slide backward and forward together with the large frame 30 while the bar 16 itself stays within the reach of the bell crank 17.

In Fig. X is illustrated the provision for keeping a particular pawl in engagement with the corresponding ratchet teeth throughout the whole travel of the ratchet bar. The pivot 61 holding each pawl is flattened on one side, with a spring piston 62 pressing against the flattened side. On a comparatively slight motion of the pawl the spring piston will persist in returning to the flattened side of the pivot, a large motion of the pawl, however, will shove the spring piston 62 entirely off the flattened surface and set the companion pawl to work instead.

The vertical rod 63 at the left-hand side near the front (Figs. I, III, and V,) which projects the fingers 64 into the path of the platform 34, is connected with a clutch 65 whereby, through the chain drive 66, the timing gear 41' is automatically set in motion whenever the platform 34 has reached the lowest position, and is automatically stopped on reaching the limit of its elevation.

How the paper carrying chains 6 are driven by bevel gears 67 from the main shaft 25 is plainly illustrated in Fig. III.

The same size of box is always used to pack a small number of large fruits or a large number of small fruits. Our machine can be adapted to all the different packs by a mere changing of the various timing gears.

There are some details of construction which will yet require considerable experimentation and study in order to obtain the best results, but the general principle of our machine has herewith been fully stated and we reserve to ourselves the right to make such changes in construction as will not violate the spirit and principle of our invention.

We claim:

1. In a fruit packing machine, the combination of a gravity grader chute, with mechanism to automatically wrap paper around a fruit, means to deposit it in layers in a box, means to automatically remove the full box, and means to substitute an empty box.

2. In a fruit packing machine, the combination of a gravity grader chute, with a

mechanism to automatically wrap paper around the bottom and sides of the fruit, said mechanism comprising a supporting stand, a table, a bench on the table, registering openings in bench and table, a paper-cutting knife rearwardly of the bench, paper carrying chains across the table, a bell-shaped piston descending on the fruit and wrapping the paper around the bottom and sides of the fruit by pressing the same through the opening in the table, with mechanisms to pack the fruit in layers in a box, means to remove the full box, and to substitute an empty box.

3. In a fruit packing machine, the combination of a gravity grader chute means to automatically wrap the fruit from the grader chute in paper, with means to automatically deposit the same in a box, said means comprising a supporting stand, a table, a tunnel under the table, a tube depending from the tunnel, a horizontal frame reciprocating at the longitudinal axis of the tunnel, with a piston descending through the table, traversing the tunnel and frame and moving the full length of the depending tube, mechanism to impart an intermittent horizontal and vertical motion to a box, and mechanism to remove a full box and substitute an empty one.

4. In a fruit packing machine, the combination of means to automatically wrap fruit in paper, and means to deposit the same in a box, with means to impart an intermittent horizontal motion to the box, said means comprising a supporting stand, a platform within the stand, a small box-enclosing frame mounted at a permanent height above the platform, a pawl and ratchet mechanism to send the small frame from one side of the supporting stand to the other, a large frame supporting the small frame slidably, and a pawl and ratchet mechanism to send the large frame with the enclosed small frame from one end of the supporting stand to the other, mechanism to impart an intermittent vertical motion to the box, and mechanism to remove a full box and substitute an empty one.

5. In a fruit packing machine, the combination of means to automatically wrap fruit, and means to deposit the same in a box, with means to impart an intermittent vertical motion to the box, said means comprising a supporting stand, a platform within the stand, ratchet bars projecting upward from the platform, pawls attached to the stand and alternately engaging the teeth of the ratchet bars, toggles between the platform and the floor to raise the platform, and mechanism to remove the full box and substitute an empty one.

6. In a fruit packing machine, the combination of means to automatically wrap paper around fruit, means to deposit the

same in a box, with mechanism to remove the full box and substitute an empty one, said mechanism comprising, a supporting stand, a box-supporting platform within the stand, a box-supporting plank outside the stand in horizontal alinement with the platform, and a carrier chain with prongs pro-

jecting above the plank, and moving from one end of said plank to the other.

Signed by us at Portland, Oregon this 10
7th day of February, 1921.

AILENE BABB.
EDWARD B. HARRIS.
